THOMAS J. BROWN, OF BELVIDERE, ILLINOIS.

Letters Patent No. 86,207, dated January 26, 1869.

IMPROVEMENT IN STUMP-EXTRACTORS.

The Schedule referred to in these Letters Patent and making part of the same.

To all whom it may concern:

Be it known that I, THOMAS J. BROWN, of Belvidere, in the county of Boone, and State of Illinois, have invented an Improved Stump-Machine; and I do hereby declare that the following is a full, clear, and exact description of the same, reference being had to the accompanying drawings, and letters marked thereon, making a part of this description, in which—

Figure 1 is a perspective representation of my invention in position for use.

Figure 2, a longitudinal sectional elevation of the central bed-piece, drum, and lever.

The nature of the present invention consists in arranging the drum to turn on a vertical shaft, and operate in combination with a lever and ratchet-stops, the latter passing through the lever, and being arranged to fall into notches in the top of the drum, by their own weight, as the lever is moved backward, thus obviating the necessity for raising the lever, when it is turned back to catch another notch, or raising it, when the rope or chain is to be paid out from the drum to reach a stump; and, further, in supporting the lever, when the machine is moving from place to place, by the same wheel which supports it when the machine is in operation; the whole being operated in combination with sheave-blocks, pulleys, chains, &c., as hereinafter shown.

A A represent the runners or sills of the machine, which are made of wood, and bolted fast to a bed-piece or centre-block, B, which is cast around a shaft, H, and thus holds it in place.

This shaft is made of wrought-iron, and sufficiently strong to withstand any strain to which it may be subjected, by means of the chain f, wound around the drum E, and a shoulder is formed on it at the top of the drum, to support a washer, V, fig. 2, on which a lever, L, bears. The upper end of the shaft passing through the lever, holds it in place.

On the lower part of the periphery of the drum are made notches, J, on which a spring pawl, K, (attached to the sill A,) falls, and holds what chain the drum has taken up, in the usual manner; and on the top of the drum are made a series of notches, F F, in which rat-

chet-stops, G G, catch, and move the drum when the lever L is turned.

These stops fit loosely in the mortises made in the lever L, and are raised over the inclined surfaces of the notches F, by the backward movement of the lever, and drop into the notches by their own weight.

By this arrangement of the ratchet-stops, lever, and drum, the operator is enabled to pull a stump where there is but little travelling-room, and also pay out the chain f to reach another stump without carrying the lever backward, as is the case when the lever L is made fast to the drum.

The outer end of the lever L is supported by a wheel, N, in the ordinary manner, but provision is made, by means of an axle-arm, M, fig. 1, to place the wheel N in position to travel with the machine when it is being moved from place to place.

P, fig. 1, represents a sheave-block, which is pivoted to the end of the bed-piece B, by means of lugs C C and bolt d, and arranged to swing and adjust itself to the position of the stump to be removed. This arrangement is important, and prevents the chain from drawing off from the pulleys R R.

Another sheave-block, T, is used, in combination with the block P, simply to multiply leverage.

Operation.

Fasten the anchor-chain W to a stump or stake, Y, as shown at fig. 1, then remove the ratchet-stops G G, and carry the chain U over the stump to be removed, and fasten it in the usual manner. The stops G G are then replaced, and the lever L moved by horse-power, or otherwise, in the direction indicated by the dart x.

Having thus fully described my invention,

What I claim, and desire to secure by Letters Patent of the United States, is—

The combination and arrangement of the drum E, sills A, lever L, arm M, stops G, centre-block B, shaft H, sheave-blocks T P, and wheel N, substantially as and for the purpose set forth.

THOMAS J. BROWN.
